HAIR CURLING DEVICE

Nathan L. Solomon, Brooklyn, N. Y.

Application June 22, 1933. Serial No. 677,051

6 Claims. (Cl. 132—41)

The invention is directed to a curling device for shaping or waving hair and more particularly is concerned with a hair curling device having complementary hair holding or gripping instrumentalities about which the hair to be curled or shaped is wound and with which a swingable resilient hair pin shaped loop cooperates for properly holding the hair wound on the complements in place. The invention has as one of its objects the provision of a hair curling device which comprises few parts for quick assembly and which may be manufactured at a relatively low cost. The invention has as another object the provision of a hair curling device having a swingable and resilient loop shaped member pivotally attached to manipulatable portions of the complements for holding the latter normally closed and for removably interlocking with one of the complements to hold the hair wound about the complements in the desired position. The invention has as another object the provision of novel means to permit the resilient hair holding loop to be swung relative to the complements so that its closed end may be conveniently interlocked with one of the complements without partially separating the complements. Other objects, advantages and features of the invention are in part obvious and in part pointed out hereinafter.

30 The invention accordingly comprises, features of construction, combination of elements and arrangement of parts which will be exemplified in the construction hereinafter set forth and scope thereof will be more particularly pointed out in the appended claims.

35 For a clearer understanding of the invention attention is directed to the several embodiments shown in the accompanying drawing in which:—

Fig. 1 is a plan view of the hair curler accord-

40 ing to the invention shown closed.

Fig. 2 is a plan view of the curler shown partly in section and illustrating the hair gripping or holding complements closed and the closed end of the resilient loop swung to a position preparatory to the separation of the comple-

45 ments.

Fig. 3 is a side view of Fig. 1.

Fig. 4 is a section on the line 4—4 of Fig. 3.

Fig. 5 is a section taken on the line 5—5 of

50 Fig. 4.

Fig. 6 shows longitudinal sections of the gripping or holding complements fastened to respective associated terminals of a common intermediate strip of metal shown in full lines while the dash and dot lines illustrate the assembly

after the strip of metal has been bent into the form of a hair pin loop to arrange the complements for their pivotal connection.

Fig. 7 illustrates in perspective a fragmentary portion of a modified hair curler.

Fig. 8 is a section along the line 8—8 of Fig. 7 and

Fig. 9 is an enlarged view of a fragmentary part of the hair curler of the types according to Figs. 1 to 8 inclusive.

According to the invention the hair curling device comprises cooperating hair holding complements 10 and 11 between which a portion of the hair to be curled is clamped and about which the hair to be curled is wound. A swingable loop 13 serves to hold the hair wound about the complements in place when swung to be interlocked with one end of complement 10, the latter being in the form of a substantially cylindrical tube having spatially arranged perforations 12. Complement 11 is in the form of a semi-cylindrical perforated tube having an inverted U shaped or concavo-convex cross section adapted to fit over tube 10. Complements 10 and 11 are made of a relatively light weight sheet metal or other suitable stock, such as aluminum or the like. It is also within the province of the invention to have the complements made of a suitable hard rubber or wood.

The tube is provided with a pair of spaced 85 perforated upstanding lugs or ears 14 and 15 which appropriately support the transversely arranged pin 16. Complementary holding element 11 is also provided with a pair of perforated depending lugs or ears as 17 which straddle the pair 90 of ears of the tube and which are pivoted on pin 16, the latter having its other ends suitably upset to hold the depending ears of complement 11 within close proximity to the upstanding ears of the tube to prevent transverse play.

In accordance with the invention each of the complements is provided with a terminal manipulatable portion for raising complement 11 away from its associated holding complement 10, that is, complement 11 comprises an upwardly and outwardly manipulatable portion or extension 18 and the tube 10 embodies a downwardly and outwardly manipulatable portion or extension 19. Each of these extensions includes a raised or boss shaped member as 20 each having an outside 105 horizontal face 21, the outside faces 21 of the bosses being disposed parallel to each other.

A spring hair pin loop generally designated 13 has its terminals 23 and 24 of its legs 25 and 26 pivotally attached to an associated horizontally 110

disposed face 21 of an adjacent boss 20. The hair pin loop is made of a suitable resilient or spring metal having a width greater than its thickness.

As shown in Fig. 1 the loop is closed, that is, 5 interlocked with the tubular perforated complement. In this position, the loop serves to maintain the hair wound about the complements in place.

In the open position of the loop as illustrated 10 in Fig. 2 and as indicated by the full lines the complements are closed but may be readily opened by first pressing the terminals of the legs of the spring inwardly such that the manipulatable portions 18 and 19 of the complements are moved 15 towards each other causing the holding complements to open, that is, to take the position as indicated by the dot and dash lines to permit the insertion of hair therebetween.

With the complements separated, the spring 20 loop is in a partially collapsed position which is indicated by the dot and dash lines. The loop also serves as a handle and may be held in one hand of the operator while the other hand is employed in winding the hair about the complements.

The tube is provided with a pair of opposed 30 indentations or grooves 27 and 28 adjacent one end thereof for receiving or interlocking with opposed strip portions as 29 of the spring loop adjacent its closed end.

The terminals 23 and 24 of the legs of the hair pin spring are pivotally attached to faces as 21 of respective bosses 20 by means of eye clasps or rivets as 30 which have their ends suitably upset as to straddle an outer face of the ends of the loop and an inside face of an associated manipulatable portion of the holding complements.

The parallel faces 21 of the bosses 20 guide the 40 loop during its movement when swung from an open to a closed position or vice versa. In its movement towards a closed position, the parallel faces guide the loop so that its closed end will not strike the tube in such a manner as to cause the holding complements to separate, that is to say, the closed end of the loop is free of the tube 45 until the opposed strip portions as 29 interlock with the cooperating grooves 27 of the tube.

In operation, the curling device is first opened, 50 by disconnecting the loop from the complement 10. The complements are then opened by finger pressing against the terminals 23 and 24.

With the complements open the ends of the hair to be curled are interposed between the complements after which the pressure is released. 55 The ends of the hair inserted are firmly held between the complements by reason of the outward thrust normally exerted on the manipulatable portions 18 and 19 by the terminals 23 and 24 of the loop thus tending to keep the complements closed.

The hair is now wound about the closed complements and the wound hair is held in place thereon by swinging the spring loop to interlock or interengage with the tubular complement 10.

In the assembly of the hair holding device, the 65 perforated complements 10 and 11 are first pivotally attached to their respective ends 23 and 24 of the spring 13 which has been previously crimped at the centre after which the complements are brought towards each other against the resistance of the spring such that complement 11 fits over the complement 10. Arranged in this fashion, the complements are pivotally attached by inserting the fulcrum pin 16 through the overlapping 75 and perforated lugs 15 and 17. The ends of pin

16 is then suitably upset to maintain corresponding lugs of the complements within close proximity. With the complements brought towards each other preparatory to their pivotal connection, the ribbon strip of metal 13 has taken the form of a hair pin shaped or U shaped loop.

In the form according to Figs. 7 and 8, the hair holding device is similar in all respects to the construction hereinbefore set forth in connection with Figs. 1 to 6 inclusive except that the spring loop 85 13 is made of a wider strip of metal and comprises opposed detents as 31 which cooperate with opposed indents or small grooves 32 on the perforated tube 10. Detents and indents 32 are utilized to permit the loop to be readily connected or disconnected from the tube, the perforations in the tube and its associated hair clamping or holding complement in the construction according to Figs. 7 and 8 as in the case of the form disclosed in Figs. 1 to 6 inclusive, serving to facilitate ventilation to permit the hair which is coiled about the complements to dry more rapidly.

In all of the forms disclosed, the inside faces of the terminals or ends 23 and 24 of the spring loop closely and movably embrace the bearing 100 surface formed by the parallel faces 21 of the bosses and by reason of the spring pressure imparted by these ends, the manipulatable portions 18 and 19 are urged outwardly and consequently the complements are normally held closed or in contact against each other.

It will also be noted that the ends as 23 of the legs of the resilient loop are slightly attenuated or swaged such that the ferrule or rivet 30 may be upset to present its outer head formed substantially within the plane of the outer face of its respective leg of the resilient loop. In this way sharp projections which would otherwise accidentally catch portions of the hair are eliminated.

As many changes could be made in the above method and many apparently widely different embodiments of the invention could be devised without departing from the scope thereof, it is intended that all matter contained in the above 120 description or shown in the accompanying drawing shall be interpreted as illustrative and not in a limiting sense.

I claim:

1. In a hair curling device of the character described, the combination of, complementary pivotally connected clamping elements adapted to hold hair and about which said hair is coiled, and a resilient loop disconnectably associated with the sides of one of said elements and having end portions pivotally attached to corresponding terminals of said elements, said end portions normally urging said terminals outwardly to maintain said elements closed.

2. In a hair curling device of the character described, the combination of, complementary perforated pivotally connected elements adapted to hold hair and about which said hair is coiled, and a resilient loop having ends pivotally attached to corresponding terminals of said elements, said ends normally urging said terminals outwardly to maintain said elements closed, one of said elements extending beyond the other and including spaced side grooves for removably interlocking with opposed parts of said loop.

3. In a hair curling device of the character described, the combination of, a perforated tube, a perforated clamping element pivotally connected to said tube, said tube and element each comprising a terminal manipulatable portion

- each including a boss having a relatively flat face, said faces being disposed in parallelism, a loop shaped resilient member comprising legs having ends movably guided on said faces and pivotally connected to said portions, said tube being provided with grooves adapted to removably interlock with opposed parts of said member, said ends being adapted to urge said portions outwardly for normally holding said clamping element against said tube. 10
4. In a hair curling device of the character described, the combination of, a perforated tube, a perforated clamping element pivotally connected to said tube, said tube and element each having a terminal manipulatable portion each including a boss having an outwardly disposed relatively flat face, said faces being disposed in parallelism and providing bearing surfaces, a hair pin loop shaped resilient member comprising legs having ends movably guided on said bearing surfaces and pivotally connected to said portions, said tube having at one end grooves adapted to removably interlock with opposed parts of the closed end of said loop, said ends normally urging the aforementioned manipulatable portions outwardly to arrange said clamping element against said tube. 15
5. In a hair curling device of the character described, the combination of, a perforated tube, a perforated clamping element pivotally connected to said tube, said tube and element each having a terminal manipulatable portion each including a boss having an outwardly disposed relatively flat face, said faces being disposed in parallelism and providing bearing surfaces, a hair pin loop shaped resilient member having a width greater than its thickness and comprising legs having ends movably guided on said bearing surfaces and pivotally connected to said portions, said tube having at one end grooves adapted to removably interlock with opposed parts of the closed end of said loop, said ends normally urging the aforementioned manipulatable portions outwardly to arrange said clamping element against said tube. 20
6. In a hair curling device of the character described, the combination of, a perforated tube, a perforated clamping element pivotally connected to said tube, said tube and element each having a terminal manipulatable portion each including a boss having an outwardly disposed relatively flat face, said faces being disposed in parallelism and providing bearing surfaces, a hair pin loop shaped resilient member having a width greater than its thickness and comprising legs having attenuated or swaged ends movably guided on said bearing surfaces and pivotally connected to said portions, said tube having at one end grooves adapted to removably interlock with opposed parts of the closed end of said loop, said ends normally urging the aforementioned manipulatable portions outwardly to arrange said clamping element against said tube. 25
